UNITED STATES PATENT OFFICE.

WILLIAM O. MOSSOR, OF LOONEYVILLE, WEST VIRGINIA, ASSIGNOR OF ONE-HALF TO
PHILIP S. WILLIAMS, OF LOONEYVILLE, WEST VIRGINIA.

LEG-WARMING BOOT.

1,199,914.

Specification of Letters Patent.

Patented Oct. 3, 1916.

Application filed March 6, 1916. Serial No. 82,476.

To all whom it may concern:

Be it known that I, WILLIAM O. MOSSOR, a citizen of the United States, residing at Looneyville, in the county of Roane and 5 State of West Virginia, have invented certain new and useful Improvements in Leg-Warming Boots, of which the following is a specification, reference being had to the accompanying drawings.

10 This invention relates to warming appliances, and particularly to a leg and foot covering of such a construction as to constitute a boot which may extend either above the ankle, extend to the knee or above the 15 knee, as may be desired.

The general object of my invention is the provision of a device of this kind having a double wall, the space between said walls being adapted to be filled with hot water, 20 steam or other heated fluids.

A further object of my invention is the provision of a leg warming boot having an inside stocking, as it may be termed, of water-proof material, and the boot being 25 adapted to receive fluid in a heated condition, and in this connection to provide means whereby the leg of the boot may be held to the leg of the wearer.

Still another object of my invention is 30 to construct this boot so that while hot water may circulate beneath the sole of the foot yet there shall be firm support for the sole.

Still another object is to so construct the 35 boot that it may be filled with hot water or either attached to the exhaust of an automobile engine or to a source of steam or other heated fluid.

Other objects will appear in the course of 40 the following description.

My invention is illustrated in the accompanying drawings, wherein:

Figure 1 is a perspective view of the warming appliance in actual use; Fig. 2 is 45 a vertical sectional view of the warming boot; Fig. 3 is a section through the sole portion thereof.

Referring to these figures, 10 designates what I will term the inner stocking. This 50 is to be made to conform to the leg and foot of the wearer and of course may be of such size as to extend either just above the ankle, to a point below the knee or above the knee, as desired. This inner stocking is 55 preferably made of linen, canvas or other

suitable material rendered water-proof by being coated or impregnated with rubber, the rubber being vulcanized. The inner stocking should be soft and flexible, and is preferably lined with flannel which is designated 60 11.

Disposed exteriorly of the stocking 10 is the boot or outer casing, designated 12. This is also made of any suitable fabric coated or impregnated with rubber so as to be entirely water-proof. The upper end of this outer wall or boot is connected to the stocking 10 at a point below the upper end of the stocking. The boot entirely surrounds the stocking and is spaced therefrom at all 70 points, but the sole 13 of the boot supports and is connected to the stocking by a plurality of connecting members, which, while affording firm support for the foot of the wearer will permit circulation of water or 75 other fluids between the sole of the shoe and the sole of the stocking. To this end I have shown the sole 13 of the shoe as formed with transversely and longitudinally extending ribs 14 which may be made of rubber or 80 other suitable material and which are preferably integral with the rubber of the sole of the boot and the rubber of the stocking. These ribs are formed with perforations, and preferably in these perforations are inserted the thimbles 15 or small tubes permitting the circulation of water beneath the foot of the wearer. Preferably the sole 13, which is made of relatively heavy rubber or 85 which may be made of leather, has an upwardly extending flange 16 at its edge conforming to the outline of the foot, the ribs 14 extending across and merging into said flange.

The upper end of the boot is formed with 90 a filling opening 17 closed by a screw threaded stopper 18. The stocking 10 extends above the upper end of the boot and is provided with any suitable means whereby it may be engaged with the leg of the 100 wearer. To this end I have shown a strap 19 which extends around the stocking, this strap preferably passing through loops 20 formed upon the stocking. It will be obvious that the tightening up of this strap 105 at the leg portion of the device may be held raised so that there will be no downward pull upon the leg of the boot or stocking. Preferably there will be a space of about one inch between the outer boot and the inner 110

stocking, this space to be filled with hot water or with other hot fluids. Preferably the lower end of the boot at the heel thereof is formed with a thimble 21, interiorly screw threaded and normally closed by a plug 22 but adapted to be connected to a nipple 23 formed upon the extremity of the pipe 24 which may extend to any suitable source of heated fluid, such for instance as the exhaust pipe of an internal combustion engine or to a source of steam or hot air. This thimble 21 also forms a drain pipe whereby the water contained within the boot may be readily drained off. It will of course be understood that the pipes 24 may be sufficiently flexible to allow a certain amount of movement to the feet of the wearer.

My improved leg and foot warmer is to be made of light weight material when wanted for use on a patient lying in bed, but is of course to be made of heavier and more serviceable material for out of door use. It is particularly adapted to be worn when riding in cold weather, but may also be used to apply heat to the leg of a patient who has the grippe, gout, rheumatism, or cold feet.

While I have illustrated this device as being particularly designed to be placed upon the foot and leg, it is of course obvious that it may be modified so that it may be placed around the hands and arms. While the foot and leg warmer may be designed to fit the leg snugly, it is obvious also that it may be large enough so that the user may slip his booted feet into the warmer without trouble. It is particularly true where the warmer only extends upward a relatively short height upon the leg. It is also obvious that the liquid or fluid contained within the warmer will act to cause the stocking to conform to the leg of the wearer, thus bringing the leg of the wearer into snug contact with the vulcanized lining and every portion of the leg will be thereby uniformly heated. This is particularly valuable in case of gout or rheumatism where heat is to be applied in the treatment thereof.

By providing the transverse ribs or septums 14 in the sole, the foot will be firmly supported and the boot can be used for walking short distances, while at the same time means is provided for circulating the heated fluid between the foot and the sole of the shoe.

While I have illustrated a boot having a leg portion designed to extend to the knee of the wearer, it is obvious that the proportions of this boot and the details of construction may be varied in many ways without departing from the spirit of my invention.

Having described the invention, what I claim is:

1. As an article of the character described, a double-walled boot, each wall comprising a leg portion and a sole portion, the walls

being spaced from each other, the inner sole being spaced from the outer sole by solid members permitting a circulation of the fluid between the inner and outer soles, and means whereby heating fluid may be filled into the space between the outer and inner walls.

2. A heating article of the character described comprising an inner wall of flexible water-proof material, an outer wall spaced therefrom and also of flexible water-proof material, the outer wall being less in height than the inner wall and attached thereto at its upper margin, the space between the outer and inner walls being adapted to be filled with heating fluid, a leg embracing strap mounted upon the inner wall above the outer wall and extending around the inner wall and adapted to hold the device in position upon a member, the outer wall being formed with a filling opening having a closure.

3. A heating boot of the character described comprising an inner water-proof stocking of flexible material, an outer wall spaced from the stocking and also formed of relatively flexible water-proof material, the stocking and the outer wall being both formed with soles held in spaced relation by relatively solid elements formed to permit circulation of fluid between the inner and outer soles, the outer wall being connected to the stocking below the upper edge thereof, and a band surrounding the upper edge of the stocking and adapted to be engaged with the leg, the outer wall being formed at its upper end with a filling opening having a closure and at its lower end adjacent the heel with an opening having a closure.

4. A heating boot of the character described comprising an inner water-proof stocking of flexible material, an outer wall spaced from the stocking and also formed of relatively flexible water-proof material, the stocking and the outer wall being both formed with soles held in spaced relation by relatively solid elements formed to permit circulation of fluid between the inner and outer soles, the outer wall being connected to the stocking below the upper edge thereof, and a band surrounding the upper edge of the stocking and adapted to be engaged with the leg, the outer wall being formed at its upper end with a filling opening having a closure and at its lower end adjacent the heel with an opening having a closure, the last-named opening being screw threaded for engagement with a nipple whereby a heating fluid may be admitted to the space between the walls.

5. A boot composed of double walls of flexible, water-proof material, the inner and outer walls having each a sole, the inner sole being spaced from the outer sole by trans-

verse and longitudinal perforated members, the outer wall being less in height than the inner wall and attached thereto at its upper edge, means adjacent the upper edge of the 5 inner wall for supporting a boot upon the leg of a wearer, the outer wall being formed with a filling opening normally closed by a stopper and the outer wall adjacent the sole and at the heel being formed with a filling

opening having a screw threaded thimble, 10 and a plug normally closing this thimble.

In testimony whereof I hereunto affix my signature in the presence of two witnesses.

WILLIAM O. MOSSOR.
